UNITED STATES PATENT OFFICE.

DANIEL D. HUYETT, OF WILMINGTON, DELAWARE, ASSIGNOR TO ATLAS POWDER COMPANY, OF WILMINGTON, DELAWARE, A CORPORATION OF DELAWARE.

MEANS FOR INSURING UNIFORM PRESSURE UPON EXPLOSIVE CHARGES OF DETONATORS.

Application filed June 23, 1925. Serial No. 39,093.

To all whom it may concern:

Be it known that DANIEL D. HUYETT, a citizen of the United States, residing at Wilmington, in the county of New Castle and 5 State of Delaware, has invented certain new and useful Improvements in Means for Insuring Uniform Pressure upon Explosive Charges of Detonators, of which the following is a specification.

10 This invention relates to means for insuring uniform pressure upon the explosive charges of detonators.

In the manufacture of detonators it is customary to deposit the explosive charge 15 used, into a large number of detonator shells or metal casings, in a single operation, and then remove the rack containing the charged shells to a press where pressure is applied simultaneously to all of the charges by means 20 of numerous metal punches, one of which enters the open end of each shell. These punches are mounted in a common press head and, with equal length punches, all charges are thus compressed to a uniform 25 height.

It is a well known fact that by any of the methods which may be employed commercially, an exactly uniform weight of charge cannot be deposited into the detonator 30 shells. This is due to the fact that the charges are measured out by first filling a series of holes of the approximate cubical content desired, with the explosive used and then permitting this charge to fall into the 35 shells. Variations in density of the explosive as well as variations in its flowing properties render it impossible to deliver charges of exactly uniform weight. As a consequence, with the usual methods of pressing, 40 the under-weight charges are under-pressed while the over-weight charges are over-pressed.

The over-pressed charges may result in 45 distorted and bulged detonator shells and there is also the possibility of rendering the charge non-explosive by over-compressing, as for example, "dead-pressed" fulminate charges. On the other hand, under-pressed charges are conducive to even greater ills. 50 The explosive charge not being firmly pressed into a common mass tends to loosen and subsequently fall out of the open end of

the detonator shell. The presence of loose explosives in the metal containers in which detonators are usually packed constitutes a 55 hazard in itself. Furthermore the possibility of detonators, from which part or all of the explosive charge has been lost, being used for setting off other explosives, may result in the well known dangerous and costly misfires.

The use of hydraulic pressure to equalize the thrust exerted by the 202 press points, mounted on the head of a fulminate seating press, presents many advantages. The one great draw back in the use of this method arises from leakage of the oil, water or other pressure medium, past the pistons and onto the press points where it comes in contact with and desensitizes the fulminate. 70

Therefore, the primary object in the present invention is to provide a hydraulic equalizing structure, of the class of the character indicated, by means of which uniform pressure may be exerted upon the explosive 75 charges while at the same time leakage of the pressure medium, to and upon the punches, will be effectively prevented.

The figure shown in the accompanying drawing is a view partly in vertical section 80 and partly in elevation, illustrating a portion of a press head constructed in accordance with the invention. In the construction illustrated, the press head comprises a cap 5, a body 6 and a base plate 7. The base plate 7 is recessed as indicated at 8 for the reception of the heads 9 of the punches 10. The body 6 is vertically channelled to constitute a plurality of cylinders 11, in which pistons 12 are mounted for vertical movement. Rods 13, which depend from the pistons, bear upon the heads 9 of punches 10 which in turn bear upon the explosive charges. The upper ends of the several cylinders 11 are in communication with a common pressure fluid conduit 14. The several pistons are suitably packed, conventional leather packing being indicated at 15, and said packing being held in place by washers and screws 16 and 17. 85 90 95

The pistons 12 carry depending sleeves 18, which are sweated or otherwise secured with fluid tight joints to the pistons. The rods 13 pass through snugly fitting tubes 19, which 100

- are sweated into the lower ends of the cylinders and project upwardly into the cylinders and within the sleeves 18. Thus, any seepage past the pistons is trapped in the spaces between the tubes and the sleeves and is carried off through an oil leakage return pipe 20; which is in communication with a conduit 21, that leads to the lower end of all of the cylinders.
- 10 Any desired pressure may be maintained in the conduit 14 and whatever pressure is maintained in said conduit will be imparted with uniformity to all of the press points, through the construction illustrated and described.
- 15 It is to be understood that the invention is not limited to the precise construction set forth but that it includes within its purview whatever changes fairly come within either the terms or the spirit of the appended claims.

Having described my invention, what I claim is:

1. A structure of the character described comprising a plurality of press points, a body of pressure fluid common to all of said points and means for imparting the pressure of the fluid to the several points.
2. The combination with a press head of a plurality of pistons mounted therein, a plurality of press points upon which pressure is exerted by said pistons and a body of pressure fluid common to all of said pistons.
3. The combination with a movable press head of a plurality of movable press points

carried thereby, a plurality of pistons mounted in the press head, one for each of the press points, said pistons exerting pressure upon the press points and a pressure fluid conduit with which all of said pistons are 40 in communication.

4. A structure as recited in claim 3 in combination with means for conducting away from the press points any of the pressure fluids which pass said pistons.

5. In combination a press head channeled to form a plurality of cylinders, a plurality of press points in alignment with said cylinders, pistons in the cylinders, rods carried by the pistons and bearing upon the press points, tubes surrounding said rods and projecting a material distance above the bottoms of the cylinders and a conduit in communication with the cylinders materially below the tops of said tubes.

6. A device of the character described comprising a plurality of press points, a plurality of pistons in alignment therewith and exerting pressure thereon, cylinders in which said pistons move, sleeves having fluid tight engagement with the pistons and movable therewith and tubes projecting upwardly from the lower ends of the cylinders into said sleeves, there being a pressure fluid discharge conduit leading from the lower 65 ends of said cylinders.

In testimony whereof he affixes his signature.

DANIEL D. HUYETT.
